JOHN F. WERDER, OF LAKewood, OHIO

DISCHARGE NOZZLE

Application filed March 9, 1931. Serial No. 521,230.

This invention relates to the art of discharge nozzles for metal containers and is adapted especially for use in connection with containers of lubricants.

5 Although capable of general utility in the pouring or discharge of liquids from a container, yet the present invention is especially advantageous when used in connection with lubricants which are stored in metal containers under substantial internal pressure so that they may be discharged therefrom under their own pressure. Experience has shown, however, that in the packaging and dispensing of gas-charged lubricants from 10 their containers, difficulty has been caused by the leaking of the same from the container through the nozzle with the result that some of the lubricant itself is lost and furthermore, the purpose of the internal pressure is defeated.

The purpose of the present invention therefore consists in the provision of a discharge nozzle with a closure therefor which may be sealed so effectively as to prevent escape of the gas-charged lubricant therefrom and which may be sealed in such effective manner without the employment of gaskets or other additional sealing means.

Other objects will appear from the following description and claims when considered together with the accompanying drawing.

Fig. 1 is a partial view in elevation illustrating the application of the present form of discharge nozzle to a cylindrical form of 35 metal container; Fig. 2 is a vertical sectional view through the discharge nozzle; Fig. 3 is a plan view thereof taken on line 3-3 of Fig. 2; and Fig. 4 is a vertical sectional view of a modified form of nozzle.

40 It is to be understood that the present disclosure is merely for purposes of illustration and that the same construction of nozzle may be applied also to other forms of containers or to discharge outlets and that there may 45 also be effected modifications or variations in the construction of the present form of nozzle as herein set forth and claimed.

In the one embodiment of invention illustrated in Fig. 1, the nozzle is placed on top 50 of a cylindrical container and at a point near

the edge thereof so that it may be employed for pouring the lubricant from the container upon tilting the same. This nozzle may be attached to the head of the container in any suitable manner.

55 The nozzle itself comprises the tubular neck or spout member 1 which is connected directly to the head 2 of the container, the body of which is indicated in a general way by reference numeral 3. The upper end portion of the neck 1 is screw-threaded, as indicated at 4, for engagement by corresponding threads upon the inside of the annular depending flange 5 of the closure member. The top portion 6 of the closure member is 60 provided with the pouring openings 7 which may be of any size and number. If so desired, a single opening 7 may be provided. In the present illustration, the openings 7 are spaced about the top of the closure and 65 are located just within the flange 5 so as to have communication with the passage 1^a when the closure member is in open position.

70 The central portion of the closure member 75 is recessed upon its inner surface, as indicated at 6^a, so as to provide an annular edge 8 of right angle form for engagement with the tapered or conical surface 9 upon the outside end portion of the neck member 1. Both 80 the closure and neck members are formed of semi-soft metal and the parts are so constructed and arranged that upon screwing the closure member to fully closed position, the right angle annular edge part of the 85 closure member will have line contact with the conical surface 9 for effective seating and sealing engagement therewith. These parts are so constructed that when the closure member is in such sealing engagement, the 90 reduced central portion of the closure member is still free of engagement with the upper end of the neck member 1.

95 As will be seen from Fig. 2, the pouring openings 7 extend through the top of the closure member at points between the annular edge 8 and the inner surface of the annular flange 5 so as to open at their inner ends for communication with the space between the conical surface 9 of the neck mem- 100

ber and the inner surface of the flange 5. Thus, there is provided what might be recognized as a circuitous passage-way from the passage 1^a through the discharge nozzle to the pouring openings 7. Also, the engagement of the closure member with the neck member 1 will cause a true and effective sealing engagement to be formed by the contact between the annular edge 8 and the conical surface 9. This is made possible by virtue of the semi-soft nature of the metal employed, and also the line contact between these parts. According to the present invention, it is possible to form only one of the members, that is, either the neck member 1 or the closure member of semi-soft material or, as above stated, both of these members may be formed of such material. As a result, the gas-charged lubricant may be maintained within the container against danger of escape, by merely screwing down the closure member in the manner explained and without the employment of any additional sealing means. In order to dispense any desired quantity of the gas-charged lubricant of the container, it is merely necessary to unscrew the closure member and tilt the container, whereupon the lubricant will find its way through the circuitous passage referred to and out through the discharge opening 7.

The present form of nozzle and closure is of a comparatively simple construction which may be manufactured and sold at comparatively low cost and at the same time, the nozzle and closure are of such construction that they will serve as an effective sealing means and also as an effective means of discharge without the employment of other parts than those herein disclosed.

40 As a modification, the closure herein disclosed may be constructed without any apertures therethrough, in which case it would serve merely as a dependable closure which is capable of being manufactured at a comparatively low cost and can be easily and quickly applied to and removed from the nozzle.

50 In the modified form of nozzle illustrated in Fig. 4, the container 10 which may be of any form, has attached thereto at its discharge opening the neck 11 which receives the plug closure member 12 by screw-thread engagement. The inner end of the member 12 is closed and of conical form, as at 13, for line contact with the edge of the annular shoulder 14 provided within the neck member 11. The inner end of the plug member 12 is provided with the transverse ports 15 which afford communication between the chamber or space within the neck member 11 and the discharge outlet 16 which extends axially thereof.

60 The extreme inner end of the closure plug 12 does not engage the bottom of the chamber in the neck member 11 but is spaced at

this point from the neck member when the plug member 12 is in fully closed position. And either one or both of the members 11 and 12 are formed of semi-soft metal so as to ensure an effective seating engagement between the surface 13 on the edge 14 when the plug is screwed into closed position. The rotation of the plug upon the shoulder 14 will cause a deformation in the metal and the formation of a sealing engagement between these members. The plug member 12 has the flange 12^a to facilitate turning of the same.

70 According to the present form of illustration, there are provided four parts 15 arranged ninety (90) degrees apart, but any 80 number may be provided, one or more, and this particular form of device may be modified in other ways also. In fact, by omission of the ports 15 altogether, this form of device is adaptable for use as an efficient form 85 of sealing closure, as above explained in connection with the form of device illustrated in Fig. 2.

90 As above stated, the invention herein set forth, is capable of various adaptations and 95 modifications, all of which are to be understood as being comprehended by the following claims.

What I claim is:

1. A discharge nozzle comprising a tubular member adapted for attachment to a discharge outlet and having a discharge opening therethrough, and a combined closure and discharge plug member having releasable means of interconnection within said tubular member and having a discharge passage therethrough, said combined member having line contact seating engagement within said tubular member at a point between the said discharge opening and discharge passage so as to prevent discharge when the plug is in seated position.

100 2. A discharge nozzle comprising a tubular member adapted for attachment to a discharge outlet and having a discharge opening therethrough, and a combined closure and discharge plug member having releasable means of intercommunication within said tubular member, and having a closed inner end and a discharge passage opening laterally therethrough near the inner end thereof, said tubular member having an inner annular edge 110 form of seat, and said plug member having its inner end portion of conical form for line contact engagement with said seat at a point 115 between said discharge opening and discharge passage so as to prevent discharge when the plug member is in seated position, one of said members being formed of semi-soft metal so as to facilitate such seating engagement.

120 3. A discharge nozzle, comprising a tubular member adapted for attachment to a discharge outlet and having a discharge opening, and a combined closure and discharge member having an inner annular portion for 130

- line contact, hermetic sealing engagement with said tubular member and having also a discharge opening located outside of said annular portion, said combined member and 5 tubular member having means of readily releasable interconnection and being adapted for permanent operative association with each other for effecting such line-contact sealing engagement therebetween and constituting 10 the only closure means during shipment, storage and usage of the container to which applied, at least one of said members consisting of semi-soft material of such degree of hardness as to be only slightly deformed so 15 15 as to facilitate such sealing engagement and to permit repeated use of the closure in such manner.
4. A discharge nozzle, comprising a tubular member adapted for attachment to a discharge outlet and having a discharge opening, and a combined closure and discharge member having a discharge opening, said tubular member having a conical surface, said combined member having an outer annular 20 flange with screw thread engagement with said tubular member and having also an inner annular edge for hermetic sealing engagement with said conical surface and being adapted for permanent operative association 25 therewith, at least one of said members being of semi-soft material of such degree of hardness as to be only slightly deformed, whereby there is produced sealing engagement by line contact between said members without other 30 sealing means during shipment, storage and usage of the container to which applied and whereby such sealing engagement may be repeatedly effected by continuous use of the same.
- 35 40 5. A discharge nozzle, comprising rotatably interengaging companion members adapted for permanent operative association with each other and having openings therethrough which are adapted for communication upon partial disengagement of said members so as to permit discharge therethrough, one of said members having a conical seat portion, and the other of said members having an annular edge portion, said portions 45 being adapted for seating and sealing engagement with each other in such manner as to completely cut off communication through the openings of said members, and constituting the only closure means during shipment, storage 50 and usage of the container to which applied, and at least one of said portions consisting of semi-soft material of such degree of hardness as to be only slightly deformed so as to provide sealing seat engagement between said members and permit repeated use 55 of the same in such manner.
- 60

In witness whereof, I hereby affix my signature.

JOHN F. WERDER.
